UNITED STATES PATENT OFFICE.

ALBERT O. BUCKIUS, JR., OF CHICAGO, ILLINOIS, ASSIGNOR TO THE NATIONAL MALLEABLE CASTINGS COMPANY, OF CLEVELAND, OHIO, A CORPORATION OF OHIO.

FRICITION DRAFT-RIGGING.

No. 832,953.

Specification of Letters Patent.

Patented Oct. 9, 1906.

Application filed June 8, 1906. Serial No. 320,734.

To all whom it may concern:

Be it known that I, ALBERT O. BUCKIUS, Jr., of Chicago, Cook county, Illinois, have invented a new and useful Friction Draft-Rigging, of which the following is a full, clear, and exact description, reference being had to the accompanying drawings, forming part of this specification, in which—

Figure 1 is a longitudinal sectional view showing my improved draft-rigging applied to a car. Fig. 2 is a plan view, and Fig. 3 a longitudinal section, of a modified form. Fig. 4 is a longitudinal section of another modification. Fig. 5 is a perspective view of the spring-case of Fig. 1. Fig. 6 is a perspective view of one of the followers, and Fig. 7 is a perspective view of one of the friction members or wedges.

My invention has relation to friction draft-rigging, and is designed to provide a simple and efficient draft-rigging of this character; and the invention consists in the novel construction, arrangement, and combination of parts, all substantially as described, and pointed out in the appended claims.

In the drawings, the numeral 2 designates the draw-bar.

3 is a yoke which extends rearwardly from the draw-bar and engages and is secured to the head 4 thereof.

Referring first to the construction shown in Fig. 1, the numerals 5 and 6 designate two followers placed face to face and having formed in their opposing faces a plurality of pockets 7, in which are seated the frictional members or wedges 8, having the oppositely-beveled surfaces 8^a and 8^b, which coact with the correspondingly-beveled faces on the pockets 7. These followers are slidably mounted upon the intermediate portion of a central rod or shaft 9, this portion being preferably square or angular in cross-section. 10 is a rear follower, and 11 is a spring-case which acts as a front follower. Interposed between the followers 11 and 5 are springs 12, and interposed between the followers 6 and 10 are springs 13. The followers 10 and 11 are arranged between suitable stops or draft-irons on the draft-timbers in any usual or suitable manner.

It will be readily seen that under either pulling or buffing stresses the followers 5 and 6 will be compressed against the intermediate

friction members or wedges 8, thereby forcing the latter into close frictional contact with the central rod or shaft 9, the friction increasing with the increasing stress. The rod 9 is preferably made somewhat shorter than the distance between the two followers, so as to permit of a certain initial compression of the springs before the friction members commence to fully act.

The construction shown in Figs. 2 and 3 is similar to that in Fig. 1, with the exception that I have shown single springs 14 instead of the double springs 12 and 13, with an ordinary follower 15 in place of the spring-case 11. In this construction the followers are mounted upon the squared through-rod 9^a.

In the modification shown in Fig. 4 I employ two pairs of followers 16 16 and 17 17, between each of which are a series of friction members or wedges 18, which are similar in their operation and arrangement to the friction members 8 first described, a single spring 19 being interposed between the two sets of followers, and the latter being arranged to slide on a square through-rod 20.

The advantages of my invention will be appreciated by those skilled in the art. The arrangement is a simple and effective one in its arrangement of friction members directly acted upon by the followers and takes up so little room that it can be readily applied to use in all cases where draft-rigging of the kind now commonly employed are applicable.

The invention may be modified in many ways without departing from the spirit and scope of my invention as defined in the claims, since

What I claim is—

1. A draft-rigging having a central member, a pair of followers slidably mounted thereon, and a friction member seated between and engaged by the followers and acting upon the central member; substantially as described.

2. A draft-rigging having a central member, a pair of followers seated thereon, a plurality of friction members between the opposing faces of and engaged by the followers, and spring mechanism acting upon the followers; substantially as described.

3. A draft-rigging having a yoke, spring mechanism therein arranged to be compressed by pulling and buffing stresses, a pair

of followers engaged by the spring mechanism, and a friction member between and engaging the opposing faces of the followers and arranged to be forced against a central friction member; substantially as described.

4. A draft-rigging having a yoke, a spring mechanism in the yoke, a central friction member, a pair of followers slidably mounted on the central friction member and having pocketed faces formed with beveled walls, and a plurality of friction members having surfaces coacting with the central member, and beveled faces coacting with the beveled faces of the pockets; substantially as described.

5. In a draft-rigging, a friction device consisting of a central member, a pair of followers slidably mounted thereon, and having

pockets or recesses in their opposing faces, and a plurality of friction members having beveled faces coacting with the beveled walls of the pockets and frictionally engaging the central member; substantially as described.

6. A draft-rigging comprising a yoke, a central through-rod forming a friction member, two pairs of followers seated on said rod and having interposed friction members, and a spring interposed between the two pairs of followers; substantially as described.

In testimony whereof I have hereunto set my hand.

ALBERT O. BUCKIUS, JR.
